UNITED STATES PATENT OFFICE

GEORGE H. GILLIGAN, OF PROVIDENCE, RHODE ISLAND, ASSIGNOR TO U. S. RING TRAVELER COMPANY, OF PROVIDENCE, RHODE ISLAND, A CORPORATION OF RHODE ISLAND

RING TRAVELER

Application filed February 20, 1931. Serial No. 517,143.

My invention relates to ring travelers of the vertical type for employment in spinning or twisting.

During the movement of this type of traveler upon the ring its upper portion is, by reason of centrifugal force, overbalanced, whereby this portion is thrown outwardly or towards the ring, thereby diminishing the area of the gap through which the yarn 5 passes, and results in bringing the yarn in too close proximity to the lubricated surface of the ring. In some cases the excessive outward tilting of the upper horn of the traveler relatively to the ring affords so 10 restricted a passage as to cause breakage of the yarn passing therethrough.

Furthermore, at present this type of traveler, when purposed for use upon relatively shallow or vertically short rings, is 15 made of excessive width in order to insure sufficient weight. This relatively great breadth of the traveler body prevents an adequate approach of the latter to the concave wall of the ring, and lessens the effectiveness of traveler performance.

The essential objects of my invention are to overcome the overbalancing of the traveler top; to afford adequate weight for the traveler body without increasing the width 20 of the latter; and to attain the above ends in a structure compact in form and inexpensive to construct.

To the above ends primarily, but not exclusively, my invention consists in such 25 parts and in such combinations of parts as fall within the scope of the appended claims.

In the accompanying drawings which form a part of this specification,

Figure 1 is a fragmentary transverse section of a spinning or twisting ring showing my present invention in side elevation in running position thereon,

Figure 2, a perspective view of my traveler,

Figure 3, a side elevation of a modified form of my traveler in position on a ring shown in fragmentary section, and

Figure 4, a rear perspective view of another modified form of my invention.

Similar characters of reference indicate similar parts throughout the views.

In the drawings 8 represents a spinning or twister ring of any usual or convenient construction suitable for insertion in the 55 ring rail of the spinning or twister frame.

My novel traveler, as shown in Figures 1 and 2, is of the vertical type, and is adapted for facile cutting and bending, by suitable tools, from a thin sheet metal blank. 60 The cut out metallic strip of material is bent to form a traveler comprising a shank represented in a general way by 10, including a lower portion 11 and a rearwardly and upwardly inclined portion 12 defined 65 by a bend or concavity 14, in this instance above the center of the shank.

The upper end of the shank portion 12 is continuous with the forwardly directed horn 16 including its usual downwardly inclined 70 terminal lip portion 17. The slightly angular loop 18 formed by the horn portion 16 and the shank portion 12 permits the passage therethrough of the thread or yarn 19 in its travel from the usual delivery rolls 75 and thread guide to the spool or bobbin.

Integral with the lower end of the shank portion 11 is a forwardly extending arcuate upturned foot or lower horn 20. The material from which the traveler is formed is at 80 the end of the foot folded rearwardly upon the lower face of the foot forming an integral strip 22 extending the length of the foot and connected to the latter by a closed loop or fold 23. The width of the longitudinally disposed strip 22 is the same as that of the foot. The strip acts as a weight or a counterweight.

In operation, as the traveler is impelled 90 in its annular course around the ring 8 under the impulse of the thread 19, the bearing portion 11 of its shank is held throughout its length in sliding contact with the inner face 25 of the ring by virtue of the 95 weight of the strip 22 which causes the shank portion 11 to assume a vertical position, thereby maintaining the thread bearing angle 18 of the traveler at a point rearwardly remote from the adjacent face 25 100.

of the ring which is covered with a lubricant.

The common traveler of the prior art, differs from applicant's present structure in the absence from the former of the gravity member 22 or its equivalent. The result is that the traveler assumes a forward tilt which brings the thread 19 closer to the lubricated surface of the ring than does applicant's traveler.

10 A modified form of my traveler, shown in Figure 3, differs from that disclosed in Figure 1 in that the strip 22 is lengthened to provide a portion 27 extending upwardly some distance upon the rear face of the shank portion; the strip portion 27 being the same width as that of the latter.

15 A further modification of the device is shown in Figure 4, wherein the gravity strip at its upper end is laterally expanded to a width in excess of the width of the traveler shank to form a horizontal laterally projecting head 29.

20 In all the forms of my invention the added weight furnished by the strip is located upon the traveler at a point below the fulcrum point 14 thereof, which is above the medial point of the shank 10.

25 In order to insure the desired perpendicular running position of my traveler it is desirable that the added weight furnished by my folded strip exceed the weight of the upper horn.

30 The application of the added weight by means of a strip folded upon itself is inexpensive and compact.

I claim:

35 1. A traveler for spinning or twisting rings comprising a shank, a horn upon the upper end of the shank, a foot, and a gravity strip upon the bottom of the foot, extending inwardly from the free end of the foot.

40 2. A traveler for spinning or twisting rings comprising a shank, a horn upon the top of the shank, a foot and a gravity strip extending longitudinally of the foot integrally connected to the free end of the foot,

45 3. A traveler for spinning or twisting rings comprising a shank, a horn upon one end of the shank, a foot upon the other end of the shank, a gravity strip extending longitudinally of the foot and in contact therewith, and a fold integrally connecting the foot and strip.

50 4. In a traveler for spinning or twisting rings, a shank comprising a vertical portion and a rearwardly and upwardly inclined portion upon the vertical portion, a horn upon the inclined portion, a foot upon the vertical portion, and a gravity strip upon the foot extending inwardly from the free end of the foot for counterbalancing the horn.

55 5. In a traveler for spinning or twist-

60 ing rings, a shank comprising a vertical portion and a rearwardly and upwardly inclined portion continuous with the upper end of the vertical portion, a horn upon the inclined portion, a foot upon the lower end of the vertical portion, and a gravity strip foldably connected with the foot extending longitudinally of the foot and engaging the vertical portion.

65 6. In a traveler for spinning or twisting rings, a shank comprising a vertical lower portion and a rearwardly and upwardly inclined upper portion, a horn upon the inclined portion, a foot upon the vertical portion, a gravity strip integral with the free end of the foot extending longitudinally of the foot and of the vertical portion of the shank, and a laterally projecting head upon the upper end of the strip.

70 7. In a traveler for spinning and twisting rings, a shank comprising a vertical portion and a rearwardly and upwardly inclined portion continuous with the upper end of the vertical portion, a horn upon the inclined portion, a foot upon the lower end of the vertical portion, and a gravity strip foldably connected with the foot extending inwardly from the free end of the foot.

75 In testimony whereof I have affixed my signature.

GEORGE H. GILLIGAN.
